LOOP-TAKER FOR SEWING MACHINES

Herbert J. Goosman, Elizabeth, N. J., assignor to
The Singer Manufacturing Company, Elizabeth, N. J., a corporation of New Jersey

Application October 10, 1933, Serial No. 692,934

22 Claims. (Cl. 112—228)

This invention relates to improvements in loop-takers for sewing machines and more particularly to lock stitch loop-takers.

The invention will be understood by reference 5 to the accompanying drawings in which:

Figure 1 is a face view of a loop-taker embodying my invention.

Figures 2, 3 and 4, are left, right and bottom 10 side views of the loop-taker as viewed in Figure 1.

Figure 5 is a back view.

Figure 6 is a face view with the thread-case removed, showing the normal position of the gib in full lines and its position, in dotted lines, when an 15 obstruction is encountered in the raceway.

Figure 7 is a sectional view taken along the line 7—7 of Figure 1.

Figure 8 is a view similar to Figure 7 showing the position of the parts of the loop-taker if 20 thread should be caught in the raceway.

Figure 9 is a disassembled perspective view of 25 the component parts of the loop-taker.

Figure 10 is a perspective view of the back of the loop-taker body and the gib.

Figure 11 is a section taken along the line 11—11 30 of Figure 5.

Figure 12 is a section taken along the line 12—12 of Figure 1.

Figure 13 is a section taken along the line 35 13—13 of Figure 1.

In the embodiment of this invention selected for 40 illustration, the loop-taker comprises a base or body 1 which is formed with a flange 2 terminating at one end in a loop-seizing beak 3 and its opposite end in a vertical wall 4 having an overhanging portion 5. Pivotedly secured to the base 1 by the pivot-screw 6, which is located beneath the overhanging portion 5 and diametrically opposite the gap in the hook-body adjacent the loop-seizing beak, is a gib 7 formed with a wall 7', an overhanging ledge 8 and a depending flange 8'. A spring 9 located in a pocket or recess 10 on the back of the hook-body 1 has an extension 11 which is seated in a groove 12 in the gib 7. The spring 9 reacting between the hook-body 1 and the gib 7 tends to constantly urge the gib in a counterclockwise direction about the pivot-pin 6. In 45 its normal position the flange 8' on the gib 7 engages the edge 13 of the hook-body, (Figure 7), the edge 13 serving to limit the movement of gib 7 in a counterclockwise direction about the pivot-pin 6.

The gib 7 is provided with a slot 14 which is formed on the arc of a circle the center of curvature being the pivot-pin 6. A shouldered screw 15 50 extends through the slot and is threaded into the

base 1 of the hook. The slot 14 and the screw 15 serve to hold the free end of the gib against the hook-body and also to limit its expanding movement. It is to be understood, however, that the screw 15 and slot 14 are not essential and that they may be omitted without materially effecting the operation of my improved loop-taker. In this connection it will be evident that the spring 9 also acts to hold the gib 7 against the base 1, the end of the spring 9 reacting against the flat loop-guard plate 16 fixed to the bottom of the loop-taker by the screw 16'.

The plate 16 is formed with a struck-up portion 17 which engages the sharp edge 2' of the flange 2. This construction avoids forming a recess or 15 opening between the plate 16 and the body of the hook in which thread may be caught during the operation of the machine. A bobbin-case 18 is formed with an annular bearing rib 19 which is received in the raceway 20 formed in the flange 20 2 and the raceway 21 formed between the overhanging flange 7' on the gib 7 and the base of the loop-taker (Figures 7 and 8). It will be understood that the raceways 20 and 21 are in the same plane and, in effect, a single raceway. The bobbin-case 18 is provided with the usual rotation-restraining finger 22 and a centrally located post 23 on which is mounted the usual bobbin-case cap 24.

When a loop-taker having a thread-case journaled in a raceway, as heretofore constructed, is used to cooperate with a needle to form stitches, thread or some foreign material is occasionally caught in the raceway with the result that the loop-taker is "jammed" and consequently the 30 entire machine rendered inoperative. One of the main causes of this difficulty is attempting to operate the machine without work under the presser-foot and with the presser-foot raised, the needle being threaded. When the machine is so 40 operated the needle-thread is seized by the loop-seizing beak of the loop-taker and drawn below the throat-plate. The needle-thread is out of control under these conditions and the needle-loop is not drawn down the beak of the loop-taker far enough for the needle-thread to be 45 seized or retained on the hook 18' formed on the bearing-rib of the thread-case. Upon continued rotation of the loop-taker body and loop-seizing beak the thread is drawn down until it 50 contacts with the bearing rib on the thread-case and when this occurs the thread is wedged into the raceway, and the loop-taker becomes "jammed".

In Figure 8 of the drawings I have shown a 55

piece of thread 25 caught in the raceway of my improved loop-taker at a point near the loop-seizing beak. As shown, the thread causes the entire thread-case to be shifted in a plane at 5 right angles to the axis of rotation of the loop-taker, the yieldable gib 7 moving from the position shown in Figure 7 to the position shown in Figure 8. It will be obvious from the foregoing that the raceway in which the bearing rib of the 10 thread-case is journaled is expandable in a plane at right angles to the axis of movement of the loop-taker during the operation of the machine.

Although I have shown my improvement applied to a loop-taker of the type shown in the 15 patent to Finch, No. 1,048,672, dated December 31, 1912, it will be apparent that it may be applied to any stitch-forming mechanism which is complementary to the needle and having a stationary member and a movable member with 20 interlocking means therebetween, the needle-thread passing between the two members, such, for instance, as oscillating and rotary shuttle machines. It will also be apparent that either or both of the flanges forming the raceway may 25 be made yieldable and it will be understood that the form, construction and arrangement of the several elements employed may be varied. Therefore, the privilege is reserved of resorting to all such legitimate changes therein as may be fairly 30 embodied within the spirit and scope of the appended claims.

Having thus set forth the nature of the invention, what I claim herein is:—

1. A circularly movable loop-taking means for 35 sewing machines including a cup-shaped body provided with an annular raceway radially yieldable to undue obstructions during the operation of the sewing machine, and a thread-carrying element journaled in said raceway.

40 2. In circularly movable loop-taking mechanism for sewing machines, a member formed with an annular wall, a thread-carrying element journaled therein, said wall being constructed to yield radially to undue obstructions during the 45 operation of the sewing machine.

3. A loop-taker for sewing machines comprising a circular loop-seizing member movable about an axis and provided with an annular raceway which is expandable in a plane at right angles 50 to the axis of said member during stitch-forming cycles.

4. A non-jamming loop-taker for sewing machines comprising a loop-seizing member movable about an axis and formed with a raceway, 55 a thread-case having an annular bearing flange journaled in said raceway, said bearing-flange being positively confined in said member against displacement in the direction of the axis of said member and yieldingly confined in a plane at right angles to said axis during the operation of the machine.

5. A non-jamming loop-taker for sewing machines comprising a loop-seizing member movable about an axis and formed with a yieldable raceway, a thread-case having an annular bearing-flange journaled in said raceway, said 65 thread-case being bodily movable in a plane transverse to the axis of said member when the flange on the thread-case encounters an obstruction in the raceway during the operation of the machine.

6. A loop-taker for sewing machines comprising a loop-seizing member movable about an axis and provided with flanges forming a raceway, 70 one of said flanges being fixed to said member

and the other flange being yieldably secured to said member for movement in a plane at right angles to the axis of said member during the operation of the machine, and a thread-case having an annular bearing-flange journaled in 5 said raceway.

7. A rotary loop-taker for sewing machines comprising a loop-seizing member movable about an axis and provided with flanges forming a raceway, one of said flanges being fixed to said 10 member and the other flange being pivoted to said member and yieldingly urged towards said first flange, the flanges being so constructed and arranged as to permit the raceway to expand 15 radially during the operation of the machine. 15

8. A circularly moving hook for sewing machines formed with a loop-seizing beak and a circular raceway having a gap therein adjacent the point of said beak, a thread-case having a bearing rib journaled in said raceway, the raceway forming portion of the hook including a radially 20 yieldable section pivotally connected to the hook-body at a point substantially diametrically opposite said gap. 20

9. In stitch-forming mechanism for sewing machines, a bobbin-carrier having a bearing rib element, a supporting element having a raceway therefor, one of said elements being formed with a pivotally yielding section movable in the plane 30 of said raceway. 30

10. A circularly movable loop-taker for sewing machines comprising a loop-taker body having a loop-seizing beak in fixed relation therewith, a raceway formed in said loop-taker body, said race- 35 way being expandable in a plane at right angles to the axis of said loop-taker body during the operation of the machine, and a thread-case having a bearing rib journaled in said raceway.

11. A circularly movable loop-taker for sewing 40 machines comprising a loop-taker body formed with a flange having a loop-seizing beak at one end thereof, said flange being provided with a raceway, a gib pivotally secured to said loop-taker body, said gib together with the loop-taker 45 body forming a raceway which is in the same plane as the raceway in said flange, means for constantly urging said gib about said pivot into contact with said loop-taker body, and a thread-case having a bearing-flange journaled in said 50 raceway.

12. A loop-taker for sewing machines comprising a loop-taker body formed with a flange having a raceway, a gib provided with a wall and an overhanging ledge pivotally secured to said 55 hook-body, said gib together with the hook-body forming a continuation of the raceway in said flange, and spring means for constantly urging said gib against said hook-body.

13. A loop-taker for sewing machines comprising a loop-seizing member having a raceway substantially rectangular in cross-section in which the bearing rib of a thread-case is journaled, a portion of said raceway being formed by a gib yieldingly urged into engagement with the hook- 65 body and having a wall and an overhanging ledge which together with the hook-body form the raceway.

14. A circularly movable loop-taker for sewing machines including an element by which the lower thread-mass is sustained, a supporting element therefor, yielding interlocking means between said elements to prevent separation of the same, said interlocking means being yieldable in a plane at right angles to the axis of said loop- 70 75

taker during the operation of the machine, and means for limiting the yielding movement of said interlocking means.

15. In lock-stitch forming mechanism for sewing machines, an element by which the lower thread-mass is sustained, a supporting element therefor, one of said elements having a circular bearing rib and the other of said elements being constructed with a raceway for said bearing rib having spaced parallel bearing walls and a third bearing wall between the planes of said parallel bearing walls, at least a portion of said third bearing wall being radially yieldable relative to at least one of said parallel walls.

15 16. A loop-taker for sewing machines comprising a member having a loop-seizing beak, a thread-carrying member, and interlocking means between said members, said interlocking means including a gib pivoted to one of said members, and a spring constantly urging said gib about said pivot into engagement with the other of said members.

17. A loop-taker for sewing machines comprising a base, a flange on said base having one end terminating in a loop-seizing beak, a pivot-pin extending at right angles from said base, a gib pivoted on said pivot-pin, a spring yieldingly urging said gib about said pivot-pin, said flange and gib being formed with an annular raceway, and a thread-case having an annular bearing rib journaled in said raceway.

18. A loop-taker for sewing machines comprising a base formed with a flange terminating at one end in a loop-seizing beak and at its opposite end in a wall having an overhanging portion, a gib pivoted to said base at a point beneath said overhanging portion, a spring reacting between said base and said gib for constantly urging said gib about its pivot, said flange and gib together forming an annular raceway, and a thread-case having an annular bearing flange journaled in said raceway.

19. A circularly movable loop-taker for sewing machines comprising a hook-body formed with a flange having a raceway and a loop-seizing beak, a gib pivoted to said hook-body, resilient means constantly urging said gib about its pivot in the plane of movement of the hook-body, said gib together with said hook-body forming a raceway

which is in the same plane as the raceway in the flange, a thread-case having an annular bearing flange journaled in said raceway, and means for limiting the movement of said gib, whereby the bobbin-case and hook-body are prevented from separating when an abnormal obstruction is encountered in the raceway.

5 20. A circularly movable loop-taker for sewing machines comprising a hook-body formed with a flange and a loop-seizing beak, a gib formed with 10 a wall and an overhanging flange pivoted to said hook-body, said gib together with said hook-body forming a continuation of the raceway in said flange, a spring located in a recess in the hook-body and having a free end which engages said gib 15 and urges it about its pivot in the plane of movement of the loop-taker, and a thread-case having an annular bearing flange journaled in said raceway.

21. In stitch-forming mechanism for sewing machines the combination with a reciprocating needle, of loop-taking mechanism, said loop-taking mechanism comprising stationary and movable members one of which is provided with a circular raceway and the other of which is provided with a bearing rib journaled in said raceway, thread-mass supporting means within the field of said raceway, said raceway being radially yieldable to abnormal obstruction during the operation of the machine, one of said 30 members also being provided with a beak movable in a fixed and invariable circular path for seizing thread-loops from said needle for passage around a lower thread-mass disposed within the field of said beak.

35 22. In stitch-forming mechanism of the lock-stitch type, a circularly moving loop-seizing member, a relatively immovable member related thereto in the performance of a stitch-forming cycle, and a supporting connection between said members including a raceway in the one and a bearing member in the other entering said raceway, said raceway having a section which is adapted to yield away from the axis of motion of said loop-seizing member during the operation of the machine, one of said members having provision for holding a mass of lower thread.

HERBERT J. GOOSMAN.
